A. H. G.

UNITED STATES PATENT OFFICE.

SOLOMON H. GOLDBERG, OF CHICAGO, ILLINOIS, ASSIGNOR TO THE WEST COAST ROOFING AND MANUFACTURING COMPANY, OF CHICAGO, ILLINOIS, A CORPORATION OF ILLINOIS.

DESIGN FOR AN ORNAMENTAL FLEXIBLE ROOFING.

45,836.

Specification for Design.

Patented May 26, 1914.

Application filed January 9, 1913. Serial No. 741,104. Term of patent 14 years.

To all whom it may concern:

Be it known that I, SOLOMON H. GOLDBERG, a citizen of the United States, residing at Chicago, in the county of Cook and State of Illinois, have invented a new, original, and ornamental Design for an Ornamental Flexible Roofing, of which the following is a specification, reference being had to the accompanying drawing, forming part thereof.

In the drawing Figure 1 is a plan view and Fig. 2 is an end view, showing my new design.

I claim:

The ornamental design for ornamental flexible roofing, as shown.

SOLOMON H. GOLDBERG.

Witnesses:

MARK D. GOODMAN,
CHARLES J. SCHMIDT.
